UNITED STATES PATENT OFFICE.

ANTON V. BOCK, OF CHICAGO, ILLINOIS.

DESIGN FOR A BREASTPIN.

Specification forming part of Design No. 5,769, dated April 16, 1872.

Specification describing a Design for a Breastpin, invented by ANTON V. BOCK, residing at Chicago, in the county of Cook and State of Illinois.

The nature of my design is clearly represented in the accompanying drawing, to which reference is made. It consists of the profile of a woman—which may be like that stamped upon one side of an ordinary gold dollar of the United States of America—surmounted by the American and the Swedish and Norwegian flags attached to diverging staffs. I prefer to set the profile in a wreath in the manner shown, but I do not consider this to be an essential element in my design.

I am aware that it is not new to use a woman's profile on breastpins, and I do not, therefore, lay claim to a breastpin with such a de-

sign. That which distinguishes my design from all others of this character is found in the flags floating over such woman's profile.

What I claim as my invention, and desire to secure by Letters Patent, is—

A design for a breastpin composed of the profile of a woman surmounted by the flags of the United States of America and of Sweden and Norway, substantially in the manner above described.

In testimony whereof I have signed my name to this specification in the presence of two subscribing witnesses.

ANTON V. BOCK.
